MAGAZINE-TYPE HEATER

Jackson G. Gilmore, Columbus, Ohio

Application January 21, 1944, Serial No. 519,158

6 Claims. (Cl. 126—73)

1

This invention relates to stoves, furnaces or other heating apparatus adapted for burning solid fuels and, more particularly, to coal-burning heaters employing internally disposed magazines or fuel storage hoppers adapted to feed fuel gravitationally to a zone of active combustion. In another of its aspects, the present invention has to do with an improved method for burning solid fuels in magazine-type heating apparatus.

Such magazine coal-burning heaters have proved to be very satisfactory to most users primarily on account of the relatively small degree of attention required to maintain prolonged operating periods between intervals of fuel replenishment. However, their operation is characteristically sluggish, particularly when the magazines thereof are charged with fresh quantities of fuel. Under such conditions, the temperature of the apparatus drops and outlet flue temperatures decrease and as a result of the decreased rate of combustion, normal operation is not restored until a sufficient amount of the new fuel is in a state of active combustion to restore normal temperatures within the heater and its associated outlet flue. A study of the operation of the conventional magazine-type coal-burning heater has revealed that when the fuel is first added, copious quantities of smoke are formed and passed to the outlet flue or chimney. This smoke continues until flame combustion takes place at the upper portion of the magazine, or at the top of the coal body disposed in the magazine. As soon as flame appears at this point, and particularly if the heater has been constructed to admit secondary air, the amount of smoke is materially reduced.

Since smoke is unburned fuel, and its formation indicates inefficient heater operation or fuel combustion, the problem faced in a magazine-type of heater, as here under consideration, is to maintain temperatures in the top of the fuel magazine, or above the coal body therein, which will effect, with adequate air supply, thorough and complete combustion of fuel volatiles as the same are generated or are released from the coal during its gravitational descent toward the zone of active combustion. In a magazine-type heater, such zone of active combustion is disposed immediately above the grate structure in the lower part of the heater. Such zone is, therefore, disposed in a plane considerably below and spaced from the top or upper portions of the fuel magazine. Furthermore, when large quantities of fresh coal are introduced into the magazine, a wide differential exists in the temperatures of the

2

active combustion zone as compared with those which obtain above the coal body.

Various attempts have been made in the prior art to minimize smoke formation in the magazine-type of heater. Generally, such attempts have consisted in diverting a portion of the air obtained from below the grate structure through flues or passages formed between the refractory lining of the furnace and its metallic outer casing,

10 in order that such diverted air may be delivered to the top of the coal magazine. However, through contact with the metallic casing of the heater and the cooler portions of the refractory lining, the temperature of such diverted air and 15 coal gases admixed therewith is ordinarily so reduced that by the time the same is introduced into the upper regions of the magazine, the same will not support or produce active flame combustion, with the result that smoke is not consumed 20 until burning gases permeate through the coal body contained in the magazine to a sufficient extent to burn any smoke which at this belated period may be present in the upper portions of the magazine.

25 Accordingly, it is an object of the present invention to provide an improved magazine-type coal-burning heater. It is another object of the invention to provide a heater of this type in which, at all stages of its active operation, smoke formation is minimized or precluded. It is a further object of the invention to provide such a heater with one or more internally disposed vertically extending restricted passages which are co-extensive with the height of the magazine and in 35 which pilot combustion of fuel gases takes place throughout the length thereof so that temperatures may be maintained above the coal body within the magazine capable of sustaining flame combustion on the part of volatiles released from

40 the fuel body within the magazine. Still, a further object is to provide means for introducing regulated volumes of atmospheric air, independently of the grate structure, into the pilot flame passage or passages within the furnace lining, so 45 that fuel gases entering such passages may be admixed with an adequate quantity of air to cause effective burning thereof in order that a hot pilot flame may be maintained at all times in the upper regions of the magazine, or immediately above the coal body therein. Again, another object is to provide a heater of this type in which the outlets of the flame passage or passages are so formed and disposed as to release a pilot flame immediately over the coal body as the 55 height of the latter gradually diminishes as a

result of the active combustion of the fuel at the grate zone and, yet, another object of the invention is to arrange the flame passage or passages within the refractory lining of the heater and in spaced relation from the heat radiating outer casting of the heater in order to reduce to a minimum any loss in temperature of the burning mixture of air and fuel gases traveling through said flame passages.

For a further understanding of the invention, reference is to be had to the following description and the accompanying drawings, wherein:

Fig. 1 is a vertical sectional view taken through a heater provided with a smoke-burning pilot formed in accordance with the present invention;

Fig. 2 is a similar view taken on the plane indicated by the line II—II of Fig. 1;

Fig. 3 is a horizontal sectional view on the plane indicated by the line III—III of Fig. 1;

Fig. 4 is a detail perspective view disclosing the lining blocks of the heater in which the air and pilot flame passages are formed.

In the specific embodiment of my invention illustrated in the drawings which, it will be understood, is but one of many possible structural forms, the numeral 10 designates the outer metallic casing of a heater of the so-called room or space type. The casing is formed at the bottom thereof with an ash pit 11 and immediately above the latter with any suitable type of grate structure 12. In this instance, the grate structure has been shown as comprising a stationarily supported outer ring 13 which carries a perforate manually movable disk 14. The front of the pit is provided with an access opening covered, as usual, by a hinged door 15, the latter being provided with shutter controlled air-admitting openings 16. Supported on the ring 13 in direct engagement with the inner surfaces of the casing 10 are vertically disposed slabs 17 of a refractory material of ceramic composition, the latter being so arranged as to provide the interior of the heater above the grate structure with a heat-insulating or absorbing lining and, also, to form in the heater a vertical coal-receiving magazine of considerable volume or coal-storage capacity. The top of the casing is provided with a heat radiating bonnet 18, in which is formed a coal-admitting opening 19, the latter being normally closed by a hinged door 20 in which is provided shutter controlled, air-admitting openings 21. Opposite to the opening 19, the bonnet is provided with an outlet flue 22 adapted for communication with a chimney or other outlet for waste products of combustion.

The particular feature of the present invention resides in providing the refractory lining at one side with a plurality of superimposed vertically arranged lining blocks shown at 23, 24 and 25. These blocks cooperate with the slabs 17 to constitute the complete lining, but the blocks 23, 24 and 25 are formed conjointly to provide an air supplying passage 26, a flame or pilot passage 27 and an auxiliary passage 28. These passages are disposed in parallel relatively communicating order and are substantially co-extensive with the full height of the lining or the coal magazine. Each of the blocks 23 and 25 is molded, extruded or otherwise formed to provide inwardly extending arcuate walls 29, which form a part of the passages 26 and 28. The walls 29 terminate in spaced relation with respect to each other to provide a restricted vertically extending slot 30, which is coextensive in length with the passages 26, 27 and 28. The

70
75

width of the slot is regulated in accordance with the particle or lump size of the coal used in the heater. Hence, when using fine or stoker grades of coal, the slot is of minimum width and when the larger or lump sizes of coal are used, the slot may be of greater width. The matter of the width of the slot is of importance in preventing the fuel from entering in any substantial degree the flame or pilot passage 27, since this passage should be kept open and free from clogging deposits. The blocks 25 each have their upper surfaces formed with inwardly facing recesses 31. Such recesses advantageously may be formed by beveling the upper surfaces of the arcuate walls 29 of the blocks 25, as at 32. It will be noted that these recesses constitute restricted slots through which gases or volatiles distilled from the coal, as the latter approaches the active combustion zone, indicated at Z, will pass for admittance into the air supplying passage 26 and the flame passage 27.

Even with the use of air which enters the coal body through the grate 12, there would be an insufficient amount of oxygen in the gases to support effective flame combustion throughout the length of the passage 27. Therefore, in accordance with the present invention, I provide the bottom of the passage 26 with an extraneous air inlet 33, in order that sufficient oxygen will be introduced into the communicating passages 26 and 27 to produce active combustion of the fuel gases and volatiles. If the heater is associated with an efficient chimney or waste gas outlet, natural draft conditions may be utilized to regulate and effect the admittance of air into the heater through the inlet 33. However, in certain instances, it may be desirable, as shown in Fig. 3, to associate with the inlet a motor driven air fan or blower 34. The upper ends of the passages 27 and 28 are in open-communication with the interior of the bonnet 18, while the upper end of the passage 26 is at least partially closed by the use of the refractory cap plates 35.

In the operation of the heater, coal is introduced into the magazine in the usual manner, filling the magazine to a desired height. Active combustion of the fuel is maintained, as is customary, on the grate structure 12, the fuel burned being virtually coke, since as the coal gravitationally descends in the magazine, its temperature is increased, causing the removal of volatiles until by the time flame combustion takes place, the fuel assumes the form of coke or devolatilized coal. Air for the burning of this coke is supplied through the grate. As the volatiles are liberated, the same are drawn into the passageways 26 and 27 by way of the recesses 31 and the slot 30 and in these passages, the gases or volatiles are admixed with atmospheric air supplied by way of the air inlet 33. As a result of this additional and independent supply of air, flame combustion of the volatiles takes place, the burning gases being transmitted through the passages 26 and 27 and into the top of the magazine. Since these burning gases possess a temperature in excess of 1400° F. when the same are emitted into the upper portions of the magazine, ignition of smoke emanating from the fuel body takes place, causing the smoke to be rapidly and thoroughly consumed and the generated heat therefrom efficiently utilized by the heater. This action takes place immediately upon the introduction of fresh coal into the heater or furnace and the operation, therefore, is in favorable con-

trast with prior types of heaters wherein the burning of smoke can be accomplished only after flame has penetrated the fuel body and allowed to emerge into the smoke chamber.

In many types of bituminous fuels, particularly, the active combustion which takes place immediately over the grate structure is such as to produce a merger of coal or coke particles, forming a fuel cake or bridge which is virtually impenetrable to the upward flow of gaseous fluids. Such a bridging of the fuel in the present invention is not deleterious, since the gases below such a bridge may readily enter the lower portions of the passages 26 and 27. Moreover, I have observed that as a result of the high temperatures in the passage 27 and its communicating slot 30, the solid fuel immediately contiguous to the slot 30 is also burned to such degree that the same is readily pervious to the passage of gases, thus overcoming the effects of coal fusion or "bridging." The operation of the heater remains the same regardless of the amount of coal introduced into the magazine at any one time. Thus the magazine may be but half filled with fuel, and yet the smoke consuming operation remains the same, or it may be filled to any other fractional part of its total holding capacity with corresponding operation.

My improved heater has been designed to consume efficiently the most difficultly burned types of coal, as for instance high volatile stoker grades of bituminous coal, giving satisfactory operation, although, of course, coal having better composition characteristics may be more advantageously employed.

It will be noted that the passages 26, 27 and 28 are formed wholly in the refractory lining and are therefore spaced from the heat radiating casting of the heater, thus maintaining high temperatures on the part of the consumable gases traveling through these passages and minimizing heat loss therefrom. While but a single set of the blocks 23, 24 and 25 have been illustrated, it will be understood that one or more sets of these blocks may be used, depending upon the size and heat capacity of the heater or furnace. Preferably, the blocks 23, 24 and 25 are separately formed merely for convenience in manufacture and assembly. However, it is obvious that said blocks may be provided in a single unit if desired.

By the use of the slot or slots 30, the coal immediately contiguous thereto will burn, thus producing localized combustion of the fuel vertically of the height of the fuel body in the magazine, overcoming the caking or bridging effect which takes place immediately over the zone of active combustion in conventional types of magazine fed heaters. When a plurality of the slots 19 are used, spaced equidistantly around the inside of the magazine or heater, such localized combustion gradually progresses toward the axial center of the magazine, thus causing the coal to gradually settle on the grate structure as it is being consumed and avoiding the need of positively forcing the coal downwardly toward the grate structure by the use of a manually wielded poker or the like in order to disintegrate caked fuel. The ash produced by my heater is characterized by its very fine and lightweight form, the same readily passing through the openings in the grate structure and into the underlying pit. With respect to the recesses 31, it will be noted that the same are normally closed by the pressing of the fuel body against the surfaces of the refractory lining. Therefore, fuel gases or air nor-

mally tend to travel lengthwise of the passages 26 and 27 until the top of the coal body is reached, at which time the gases exit through the recesses. However, this action may vary from time to time when pressure differences exist on opposite sides of the recesses. Such differences, however, have not proved to be of any practical importance.

My improved heater has the advantage of simplicity in its mechanical construction, providing for low cost manufacture. While a so-called room or space heater has been illustrated in the accompanying drawings having a combustion chamber and fuel magazine formed in accordance with the present invention, nevertheless, it will be understood that said combustion chamber and magazine may be embodied in many different types of heaters or furnaces having various control devices well known in the art and I therefore reserve the right to employ my invention in all styles of heaters in which the principles of construction and combustion above set forth may be used advantageously.

I claim:

25 1. Apparatus for burning solid fuel having an outer casing, a grate structure, a fuel receiving magazine above said grate structure, a ceramic lining for said magazine, and a bonnet above said lining, that improvement which comprises 30 a vertically extending flame-conducting flue formed wholly within the confines of said lining, said flue extending vertically of the lining from substantially the grate structure to said bonnet and communicating with the interior of said 35 magazine by a vertical slot of restricted width and a plurality of vertically spaced substantially horizontally disposed recesses, and air-supplying means independent of said grate structure for introducing regulable quantities of air into said 40 flue to sustain combustion of fuel volatiles therein.

2. A refractory magazine lining for coal burning heaters comprising superposed groups of ceramic blocks, said blocks being formed to provide a plurality of parallel vertically extending relatively communicating fluid passages, the fronts of said blocks being provided with arcuate extensions, said extensions terminating in relatively spaced order to provide a restricted vertically disposed slot openly communicating with the inwardly formed passages, the blocks at one side of said lining being formed with substantially horizontally disposed recesses constituting restricted ports communicating with the internal passages.

3. Solid fuel burning apparatus comprising a casing, a grate structure in the bottom of said casing, a smoke chamber in the top of said casing, there being a fuel magazine formed within said casing between said grate structure and smoke chamber, a refractory lining for said magazine having formed solely within the confines thereof a plurality of adjacent and vertically extending flue passages, the said passages communicating with each other by a restricted vertically extending slot and one of said passages communicating with the interior of said magazine by a restricted vertically extending slot, said flue passages being additionally in communication with the interior of said magazine by a plurality of vertically spaced and relatively restricted horizontally disposed slots formed in said lining, and means independent of said grate structure for introducing atmospheric air into said passages in quantity sufficient to sustain combustion of fuel volatiles,

said volatiles while in an active state of combustion being dischargeable from said passages into said smoke chamber to effect active burning of smoke and volatile fuel products present in said chamber.

4. Solid fuel burning apparatus comprising a casing, a grate structure in the bottom of said casing, a fuel-receiving magazine provided in said casing above said grate structure, a refractory lining for said magazine, said lining embodying a plurality of vertically arranged superimposed blocks of ceramic composition, certain of said blocks being formed internally to provide a pair of relatively communicating vertically extending parallel passages, one of said passages being in communication with the interior of said magazine by the presence of a restricted vertically disposed slot which is substantially coextensive with the length of said last-named passage, and the other of said passages being in communication with said magazine by the presence of a plurality of substantially horizontally disposed restricted ports formed in said blocks, means independent of said grate structure for admitting regulated quantities of air into the lower ends of said passages for upward travel therethrough, and a bonnet provided at the top of said casing and forming a smoke chamber, said chamber being in open communication with the upper end of at least one of said passages.

5. A refractory lining for magazine-type combustion coal-burning heaters, comprising a plurality of ceramic blocks adapted to be arranged in vertically superposed order within the casing of an associated heater, certain of said blocks being formed internally with parallel vertically extending and relatively communicating passageways for the travel of volatile fuel products and gases, the blocks containing said passageways being formed on one side with arcuate extensions, the latter being terminated in spaced relative order to provide therebetween a restricted vertically extending slot communicating with said passageways, and a plurality of substantially horizontally extending recesses formed in the blocks containing said passageways, said recesses constituting restricted ports when the blocks are in assembled order and which communicate with said passageways.

6. Solid fuel burning apparatus comprising a casing, a grate structure in the bottom of said

casing, a smoke chamber in the top of the casing, there being a fuel magazine formed within said casing between said grate structure and smoke chamber, a refractory lining for said magazine embodying a region of substantially uniform cross sectional thickness and a localized region of increased cross sectional thickness, said region of increased thickness being formed wholly within its confines with a vertically extending fuel combustion passage, the latter being substantially coextensive with the full height of the magazine and in communication with the interior of the latter by a restricted vertically disposed slot, said region of increased thickness being additionally formed with a flue extending parallel with said passage in immediately adjacent order thereto and communicating with said passage by a restricted vertically extending slot, said flue communicating with the interior of said magazine by the presence of a plurality of vertically spaced and horizontally disposed slots, and means independent of said grate structure for introducing atmospheric air into the lower portion of said flue in quantity sufficient to sustain combustion of fuel volatiles present in the combustion passage, said volatiles while in an active state of flame combustion being dischargeable from the combustion passage into said magazine above the fuel contained therein and into said smoke chamber to effect active burning of smoke and volatile fuel products present therein.
